Inventor:
Stephen Oliver Lange,
69 Lippay & Englund
His Attorneys.

UNITED STATES PATENT OFFICE.

STEPHEN OLIVER LANGE, OF ST. LOUIS, MISSOURI.

MAILING PACKAGE.

Application filed May 3, 1922. Serial No. 558,035.

To all whom it may concern:

Be it known that I, STEPHEN OLIVER LANGE, a citizen of the United States, residing at St. Louis, Missouri, have invented a new and useful Mailing Package, of which the following is a specification.

This invention relates to improvements in mailing packages, and consists in the novel construction hereinafter shown.

10 An object of the invention is to provide a mailing package including a two compartment envelope having one compartment designed to receive a reversible address card and the other for the reception of papers, 15 and including a separate fabric container connected with the envelope.

Another object of the invention is to provide a mailing package of the class described having a novel mounting for the postage, 20 whereby a plurality of stamps are arranged so that cancelled stamps may be removed and as an incident to the removal of the cancelled stamp an uncancelled stamp is displayed for postage purposes.

25 Additional advantages of the construction will be apparent from the following detailed description thereof, taken in connection with the accompanying drawings, in which

Fig. 1 is a front view of the package in 30 assembled condition for mailing.

Fig. 2 is a reverse view of the package in the same assembled condition as shown in Fig. 1.

Fig. 3 is a view of the extended envelope 35 blank and the annexed fabric container.

Fig. 4 is a face view of the insertable address card.

Fig. 5 is a reverse view of the same.

Fig. 6 is a cross section taken on the 40 line 6—6 of Fig. 1.

Fig. 7 is a vertical section taken on the line 7—7 of Fig. 1.

Fig. 8 is a view of the extended envelope blank without the attached fabric container.

45 Fig. 9 is a front view of the package without the fabric container.

Fig. 10 is a reverse view of the same.

Fig. 11 is a face view of the insertable address card used in the envelope without 50 the fabric container.

Fig. 12 is a reverse view of the same.

Fig. 13 is a view of a coupon card in-

sertible in the supplement compartment of the envelope.

Fig. 14 is a cross section taken on the 55 line 14—14 of Fig. 9.

Two forms of the invention are illustrated in the drawings, Figs. 1 to 7 inclusive illustrating a mailing package in which a fabric container is attached to the envelope portion 60 of the package, and Figs. 8 to 14 inclusive illustrating the envelope without the fabric container. In each instance the envelope portion is made up of a blank having panels 1, 2 and 3, the panels being separated by 65 score lines 4 and 5 respectively upon which the panels are foldable. At one end of the panel 2 is a gummed flap 6 and at the end of the panel 3 is a gummed flap 7.

In forming the envelope the panel 1 is 70 folded inwardly on the score line 4, and the panel 3 is then folded over the outer face of the panel 1 and the gummed flap 7 is folded over the lower front edge of the panel 2. This arrangement secures the parts 75 together in such manner that the panel 1 constitutes a partition through the envelope dividing it into a front and rear compartment. The panel 2 has a cut-out portion 80 in which any suitable transparent window 9 may be mounted.

In the embodiment of the invention in which the fabric container is attached to the envelope the container itself, in the form of a bag 10 having one end closed and the 85 other end open and having one wall thereof adjacent to the open end extended as indicated at 11, is attached to the end of the envelope by doubling over the extended wall of the container between the body of the 90 envelope and the flap 6 which flap is turned over the extended portion of the fabric container and secured to the body of the fabric container, leaving the open portion of the fabric container adjacent to the back face 95 of the envelope portion of the container. The opposite end of the fabric container has a stiff piece of card board 12 or the like inserted therein, and a staple 13 or other securing device is inserted through the strip 100 12 with the head thereof inside the fabric container and the prongs extending outwardly.

A loose flap 14 is provided at the opposite

end of the panel 2 so that when the fabric container 10 is folded inwardly against the back face 3 of the envelope body the flap 14 is turned in between the panels 1 and 3, with the prongs of the fastening device extending through openings 15 and 16 in the walls of the flap 14 and the body portion of the envelope and through openings 16^a in the panels 1 and 3.

10 In assembling the envelope for mailing purposes a reversible address card 17 is provided. This card has an opening 18 therethrough through which the prongs of the securing device extend when the address card is placed in position in the front compartment of the envelope portion of the package. By reversing the card a return address will be displayed through the window portion of the envelope thereby providing means for sending and returning the package without the necessity of separately addressing the same.

On the front face of the envelope portion is a postage mounting comprising a plurality 25 of flaps of paper, the bottom one of which is secured directly to the paper by the auxiliary flap 19, said flap being turned over at its upper end providing a secondary flap.

20 Postage stamps 21 are secured to the front face of each of the flaps, said postage stamps being superimposed on each other and being removable from the postage support by tearing the uppermost flap from the support, thus exposing the stamp carried by 35 the subjacent flap of the postage stamp support.

The supplemental or rear compartment of the envelope section of the package is designed to contain a coupon card 22 or may 40 be utilized for maintaining any other paper such as a bill, invoice or the like.

The mailing package of the present construction has many applications, but is particularly designed for the mailing and return of photographic films and prints. The 45 customer may be supplied with the packages upon which appears on one side of the address card the name of the establishment to which it is desired to send the film for development. The customer places his name 50 on the reverse side of the address card and places the coupon card in the supplemental compartment of the envelope. The establishment upon developing the films reverses 55 the address card, places the coupon, together with the negatives and prints in the rear compartment of the envelope, reassembles the package, removes the upper flap of the postage stamp support and remails the 60 package.

65 By giving an example of the use of the package it is not in any wise intended to limit its use to such purposes, as other applications for use will readily suggest themselves.

I am aware that the invention may be modified in certain particulars without departing from the spirit and scope thereof. I do not limit myself unessentially, but what I claim and desire to secure by Letters Pat- 70 ent is:—

1. A mailing package, comprising a two compartment envelope having a free flap for closing the envelope, one of said compartments having a window, a reversible address card arranged to be inserted in one of said compartments so as to be visible through said window, a fabric container attached to one end of said envelope body and being foldable inwardly, and means for attaching the free end of said fabric container and also securing the free flap of the envelope in position.

2. A mailing package, comprising an envelope body, an open-ended fabric container having one wall adjacent to the envelope body connected therewith, said fabric container being foldable over the rear face of the envelope body, and releasable means for closing the end of the envelope and also for holding the closed end of said container in position across the rear face of the envelope body.

3. A mailing package, comprising an envelope composed of three parallel panels, said panels being foldable so as to provide a partition wall dividing the envelope into two compartments, a securing flap at the edge of one of the end panels, a securing flap at the end of the center panel, a free flap at the other end of the panel, a window in the center panel, said panels being so arranged and said flaps being so disposed that when folded they will comprise a double-compartment envelope sealed on three sides and having one end thereof adapted to be closed by said free flap, and a fabric container having one end open and permanently secured to said panel and the other end closed and releasably secured to said panel.

4. In an envelope, a postage support comprising a plurality of leaves secured together at one adjacent edge thereof and adapted to receive postage stamps and being successively removable to expose subjacent postage stamps supported by the leaves for successive cancellation thereon during successive trips, the outermost stamp being adapted to carry the envelope on its initial trip and to be cancelled during such transit, a fabric container having one end open and permanently secured to said envelope and the other end closed, and means engaging the closed end of said container holding said container flat against the envelope in position to prevent the contents of the container from working out of the open end.

5. A mailing package, comprising envelope structure sealed on its top and bottom edges and at one end, and open at the oppo- 120 125 130

site end and having a flap for closing the open end, a fabric container having one end thereof open and having a wall thereof adjacent to the open end extended, means for securing said extended portion of the fabric container to one end of the envelope, a strip of stiff material inserted in the closed end

of said container, and a fastening device supported by said strip and being adapted to releasably secure the closure for the open end of the envelope and to hold the container in place against the rear face of the envelope.
